UNITED STATES PATENT OFFICE.

BERT CURTISS, OF YPSILANTI, AND GEORGE F. CURTISS, OF PLYMOUTH, MICHIGAN.

DIRECTION-SIGNAL AND ALARM.

1,243,266.

Specification of Letters Patent. Patented Oct. 16, 1917.

Application filed August 15, 1916. Serial No. 115,035.

To all whom it may concern:

Be it known that we, BERT CURTISS and GEORGE F. CURTISS, citizens of the United States, residing at Ypsilanti and Plymouth, respectively, in the counties of Washtenaw and Wayne, respectively, and State of Michigan, have invented certain new and useful Improvements in Direction-Signals and Alarms, of which the following is a specification.

This invention contemplates an improved direction signal and alarm for motor vehicles and has as its primary object to provide a device of this character wherein a driver may apprise a following driver of an intention to turn either to the right or left or stop, and at the same time, sound an alarm to thus attract the notice of the driver following to the signal displayed.

The invention has as a further object to provide a device of this character which will be electrically operated and wherein the device will operate to simultaneously give a signal and sound the alarm.

And the invention has as a still further object to provide a device of this character which will be compact, which may be easily applied to motor vehicles of any conventional type and wherein the mechanism of the device will be housed within a suitable casing so that it will be protected from the weather and will thus not be likely to get out of order.

Other and incidental objects will appear as the description proceeds and in the drawings wherein we have illustrated the preferred embodiment of the invention and wherein similar reference characters designate corresponding parts throughout the several views.

Figure 1 is a perspective view of the device with the side and top walls of the casing removed and particularly showing the mounting of the gate which carries the screen employed for giving a signal.

Fig. 2 is a sectional view more particularly showing the arrangement of the mechanism of the device within the casing therefor,

Fig. 3 is a plan view with the casing shown

in section and illustrating the actuating mechanism for the gate,

Fig. 4 is an end elevation showing the door arranged at one end of the casing, and

Fig. 5 is a diagrammatic view showing the electrical connection which may be employed in connection with a pair of the devices when mounted upon a vehicle.

In carrying out the invention, a casing is employed which includes a bottom wall 10, a top wall 11, and a side wall 12. This casing may be formed of sheet metal or other suitable material and is preferably of the general shape illustrated. At one end of the casing, the side wall 12 thereof is provided with an opening closed by a hingedly mounted door 13 carrying a suitable transparent pane 14. Any approved type of latch 15 may be employed for normally holding the door closed. Mounted in the adjacent extremity of the casing and connected with the bottom wall 10 thereof, is a lamp socket 16 which may be of any approved type and detachably receives an incandescent lamp 17, arranged opposite the door 13 so that the light from the said lamp will shine through the pane 14 of the door.

Mounted within the casing, adjacent the extremity thereof, opposite the lamp socket 16, are solenoids 18 supported by a bracket 19 connected to the bottom wall 10 of the casing. Associated with the said solenoids, in the usual manner, is a bell tapper 20 of an alarm. This tapper is bent to project freely through a suitable opening in the top wall 11 of the casing and is arranged to cooperate with a bell 21 mounted upon the said top wall and held in position thereon by a bracket 22.

Mounted upon the bottom wall 10 of the casing adjacent the solenoids 18, are co-acting solenoids 23 coöperating with which is an armature 24. This armature is swingingly supported by a shaft 25 pivotally mounted upon suitable posts 26 upstanding from the bottom wall 10 of the casing. Projecting forwardly from the armature 24 is an arm 27 to the outer extremity of which is swingingly connected a link 28 having an inwardly directed lower terminal or arm 100

29 freely engaged with one arm of a bell crank lever 30. The bell crank lever 30 is pivotally supported by a bracket 31 upon the bottom wall 10 of the casing with the 5 other arm thereof projecting upwardly and pivotally receiving a link 32. Mounted upon the bottom wall 10 of the casing in advance of the bracket 31 is a bearing plate 33 adjacent the inner extremity of which are arranged 10 upstanding posts 34 and 35 respectively. Pivotally mounted upon the post 34 and supported thereon by a suitable collar, as best shown in Fig. 2 of the drawings, is a toothed segment 36, the inner extremity of which is extended to provide an upwardly and rearwardly directed arm 37 having the link 32 pivotally connected thereto at its adjacent terminal. Removably fitting over the upper end of the post 34 and detachably 15 connected to the upper extremity of the post 35 is an angle plate 38 having one arm thereof free and projecting forwardly toward the outer end of the segment 36. As will now be clear, energization of the sole- 20 noids 23 will attract the armature 24 to move the link 28 downwardly and consequently swing the bell crank lever 30. Movement of the bell crank lever 30 will, through the medium of the link 32 correspondingly 25 swing the toothed segment 36 upon the post 34.

Mounted to coöperate with the lamp 17 is a signaling screen including a segmental body 39 from which depends a frame 40 having upper and lower longitudinally curved channel members 41 for receiving a transparent colored plate 42. The plate 42 may be formed of celluloid, glass, or other suitable material and will be preferably colored red so that when the screen is swung to active position, as shall be presently described, a red signal light will be projected through the door 13 upon the energization of the filament of the lamp 17. Swingly 45 supporting the screen within the casing is a rock shaft 43 which, at its lower extremity, is received by the bearing plate 33 and at its upper extremity, is engaged by a bearing screw 44 adjustable through the top 50 wall 11 of the casing with the body 39 of the screen fixed to the shaft adjacent its upper extremity. The shaft 43, adjacent its lower extremity, is arranged to abut the free arm of the angle plate 38 with the arm providing 55 a bearing for the said shaft intermediate its ends and mounted upon the shaft between the said arm and the bearing plate 33, is a pinion 45 arranged to coöperate with the toothed segment 36. Thus, upon the 60 pivotal movement of the said segment, as previously described, the shaft 43 will be rotated and the screen swung from inactive position at one side of the door 13 to active position with the plate 42 arranged in front

of the pane 14 of the door so that the light 65 from the lamp 17 may shine through the said plate and through the pane for giving a signal.

Connected to the frame 40 of the screen at one side thereof, is a suitable spring 46 70 which, at its inner end, is attached to a screw or other suitable terminal 47 carried by the wall 12 of the casing at one side thereof with the said spring normally tending to urge the screen to inactive position. Arranged to limit the screen in its movement under the influence of the spring 46, 75 is a stop 48 while a similar stop 49 is provided for limiting the said screen in its movement to active position.

As will now be observed, all of the mechanism of the device is inclosed within the casing so that the said mechanism will not be exposed to the weather and will thus 80 not be likely to get out of order. Adjacent the door 13, the top wall 11 of the casing is arranged to overhang the door as more particularly shown in Fig. 2 of the drawings, to provide a protection therefor. However, should any water gain entrance to 85 the casing, drain openings 50 are provided in the bottom wall 10 thereof to guard against the possibility of the water being retained within the casing.

In use, one of our improved devices may be attached to the rear of a vehicle in any approved manner at each side thereof. Suitable electric conductors or wires 51 are carried from a battery or other convenient 90 source of electrical energy to each of the said devices and are connected to the terminals of the coating solenoids 23, the terminals of the solenoids 18, and to the terminals for the lamps 17, these all being included in a single circuit having a two-point switch interposed therein. Such switch may be conveniently located upon the vehicle adjacent the driver's seat. Consequently, the driver by properly operating 95 the said switch as will be well understood, may close a circuit with either one or the other of the said devices depending upon whether a right turn or left turn of the vehicle is intended. Upon reference to Fig. 1, it will be observed that current flowing 100 through the wires 51 will, through the medium of the solenoids 18 and 23, ring the bell 21 to sound an alarm and simultaneously actuate the screen in the manner previously described to shift the plate 42 in front of the lamp 17. Also, the said lamp will be simultaneously lighted for giving a signal at the side of the vehicle corresponding to the direction in which it is intended 105 to turn. In this connection, attention is directed to the fact that the spring 46 will normally hold the screen away from the door opening so that the headlights from 110

approaching vehicles will not be reflected against the colored plate 42 of the screen and thus deceive an approaching driver by the observance of a false signal.

- 5 It will therefore be seen that we provide an exceedingly simple and efficient construction for the purpose set forth wherein a driver may easily signal the driver following an intention to turn or stop and wherein 10 an alarm will be simultaneously sounded for attracting the attention of the driver following to the signal and while we have indicated that two of the devices are preferably employed upon a vehicle, still, one 15 may be used and will be found efficient.

Having thus described the invention what is claimed is:

1. A device of the character described including a casing provided with an opening, 20 a rock shaft journaled at one end upon the bottom wall of the casing, a bearing screw adjustable through the top wall of the casing and engaging the opposite end of said shaft, a screen body connected to the 25 shaft with the said shaft supporting the body to swing in front of said opening, and means for rocking said shaft.

2. A device of the character described including a casing provided with an opening, 30 a rock shaft journaled at one end upon the bottom wall of the casing, means carried by the top wall of the casing and engaging the opposite end of the shaft, a screen body connected to said shaft with the shaft supporting the said body to swing in front of 35 said opening, a post upstanding from the bottom wall, a bracket connected to said post and providing a bearing for the shaft intermediate the ends thereof, and means 40 for rocking said shaft.

3. A device of the character described including a casing provided with an opening, a bearing plate mounted upon the bottom wall of the casing, a rock shaft journaled at one end upon said plate, means carried by the top wall of the casing and engaging the opposite end of said shaft, a screen body connected to the shaft with the shaft supporting the said body to swing in front 50 of said opening, upstanding posts connected to said plate, an angle bracket connected to said posts and having one end thereof engaging said shaft to provide a bearing therefor intermediate the ends of the said shaft, 55 and means for rocking the said shaft.

4. A device of the character described including a casing provided with an opening, a rock shaft journaled at one end upon the bottom wall of the casing, means carried by 60 the top wall of the casing and engaging the opposite end of said shaft, a screen body connected to the shaft with the shaft supporting said body to swing in front of said opening, a post upstanding from the bottom

wall of the casing, and a toothed segment 65 mounted to swing upon the said post and operatively engaging said shaft for rocking the shaft.

5. A device of the character described including a casing provided with an opening, 70 a rock shaft journaled at one end upon the bottom wall of the casing, means carried by the top wall of the casing and engaging the opposite end of said shaft, a screen body connected with the shaft with the shaft supporting the said body to swing in front of 75 said opening, a post upstanding from the bottom wall of the casing, a bracket connected to said post and engaging the said shaft to provide a bearing therefor intermediate the ends of the shaft, and a toothed segment mounted to swing upon the said post and operatively engaging the shaft at 80 a point between the said bracket and the bottom wall of the casing for rocking the 85 shaft.

6. A device of the character described including a casing provided with an opening, a rock shaft journaled at one end upon the bottom wall of the casing, means carried by 90 the top wall of the casing and engaging the opposite end of the shaft, a screen body connected to said shaft with the shaft supporting the said body to swing in front of said opening, a stop carried by the side wall 95 of the casing at one side of said opening for limiting the screen body in its movement to active position, a stop carried by the side wall of the casing at the opposite side of said opening for limiting the screen body 100 in its movement to inactive position, yieldable means connected to the screen body for normally holding the said body in engagement with said last mentioned stop, and means operatively engaging with said shaft 105 for rocking the shaft to swing the screen body against the tension of said yieldable means.

7. A device of the character described including a casing provided with an opening, 110 a rock shaft journaled between the top and bottom walls of the casing, a screen body connected to said shaft and supported thereby to swing in front of said opening, a post upstanding from the bottom wall of the 115 casing, a toothed segment mounted to swing upon the said post and operatively engaging said shaft for rocking the shaft, said segment being extended at its rear extremity to provide an arm, an electro-magnet, a 120 pivoted armature for the magnet, a bell crank lever mounted upon the bottom wall of the casing, a link connecting one arm of said lever with the arm of said segment, and a second link connecting the other arm of 125 said lever with said armature with the armature operable for swinging the said segment.

8. A device of the character described including a casing provided with an opening, a screen arranged to swing in front of said opening and including a rock shaft for supporting the screen, a swingingly mounted toothed segment operatively engaging said shaft for rocking the shaft, an electro-magnet, a pivoted armature therefor extended to provide an arm, a bell crank lever mounted upon the bottom wall of the casing, a link connecting one arm of said lever with

the said segment, and a link connected at one extremity to the arm of said armature and bent at its opposite extremity to provide an arm engaging with the other arm of 15 said lever with the armature operable for swinging the said segment.

In testimony whereof we affix our signatures.
